ALFRED MOLSTAD, OF DEDHAM, IOWA.

ROTARY VALVE FOR EXPLOSIVE-ENGINES.

1,326,682.

Specification of Letters Patent. Patented Dec. 30, 1919.

Application filed July 10, 1917. Serial No. 179,758.

To all whom it may concern:

Be it known that I, ALFRED MOLSTAD, a citizen of the United States, residing at Dedham, in the county of Carroll and State 5 of Iowa, have invented certain new and useful Improvements in Rotary Valves for Explosive-Engines, of which the following is a specification.

This invention relates to an improved 10 valve of the rotary type for an internal combustion engine and the principal object of the invention is to provide a rotary valve which may be used in connection with an internal combustion engine of the multiple 15 cylinder type and which is so constructed that the cylinder forming the movable member of the valve may serve both as an inlet and an exhaust.

Another object of the invention is to so 20 construct the valve so that the cylinders may be caused to operate in timed relation and to further so construct this valve that leakage will be prevented.

Another object of the invention is to so 25 construct this valve that the exhaust and the inlet will not interfere with each other or cause the valve to be large or cumbersome.

Another object of the invention is to provide 30 a rotary valve which is so constructed that it may be placed on top of the engine where it will be out of the way.

Another object of the invention is to so 35 construct this valve that it may be operated from the driving shaft of the engine.

This invention is illustrated in the accompanying drawings, wherein:—

Figure 1 is a view showing an engine in side elevation and provided with the improved 40 valve,

Fig. 2 is a longitudinal sectional view through the improved valve and the upper portion of a two cylinder engine,

Fig. 3 is a view showing the valve cylinder in section and the core in elevation,

Fig. 4 is a transverse sectional view through the valve taken along the line 4—4 of Fig. 2, and

Fig. 5 is a transverse sectional view taken 50 along the line 5—5 of Fig. 2.

The engine in the accompanying drawing is a two-cylinder engine but it is to be understood that any number of cylinders could be provided and in case of a greater number 55 of cylinders, it would simply be necessary to increase the length of the valve and dupli-

cate the parts thereof. This engine is indicated in general by the numeral 10 and is provided with the cylinders 11 and 12 having the ports 13 which ports serve as inlets 60 and as exhaust ports. It will thus be seen that the charge will be sucked in through the ports 13 and after being fired, the burnt gases will be forced out through these ports by the pistons. This engine is provided 65 with the usual crank casing 14 and with a crank shaft 15 which extends beyond the end of the crank casing 14 and carries the fly wheel 16 and a pulley about which passes the belt or flexible drive 17 for a purpose 70 to be hereinafter brought out.

The rotary valve is provided with a cylinder or body 18 mounted upon the engine and extending longitudinally thereof. This cylinder or body 18 is closed at its ends by the 75 heads 19 and 20, the heads being provided with a center bearing 21 and the head 19 being provided with a neck or conduit pipe 22 leading to the carburetor 23. The cylinder or body 18 incloses the port 13 and is 80 further provided with an exhaust port 24 from which leads the exhaust pipe 25.

In order to control the passage of the live gases and the burnt gases through the casing or cylinder 18, there has been provided 85 a rotary valve provided with a tubular core 26 closed at one end and terminating in a stub shaft 27 and having its opposite end open and rotatably mounted in the sockets 28 of the head 19. Sleeves 29 and 30 are 90 cast about the end portions of the core 26 and are provided with ports 31 registering alternately with the ports 13 for admitting live gas to the cylinders. The sleeves are further provided with ports 32 for permitting burnt gases to pass from the cylinders 95 into the pockets or chambers 33. Both chambers 33 are in constant communication with a central annular channel 34 between the sleeves 29 and 30 and this channel in turn 100 communicates constantly with the exhaust port 24. Grooves 35 are provided to carry lubricating oil thus permitting the core to rotate easily.

When this engine is in operation, rotation 105 of the engine shaft will transmit rotary movement to the stub shaft 17 through the medium of the belt 17 which passes about pulley wheels carried by the crank shaft 15 and the stub shaft 27 and this will cause 110 the core to rotate thus bringing the inlet ports 31 and exhaust ports 32 alternately

- into registry with the cylinders or ports 13. It should be noted that these ports 31 and 32 are so located that the ports 31 for one cylinder will be brought into registry with the port 13 and a charge of gas sucked into the cylinder. The core will then rotate and upon return stroke of the piston, the gases will be compressed. The firing stroke will then take place and as the piston returns for the exhaust stroke, the port 32 will register with the port 13 and the burnt gases will be driven out of the cylinder and through the ports 32 into the chamber 33 and will then pass from this chamber into the space 34 and through the exhaust pipe 25. It will thus be seen that a very efficient valve has been provided and it will be further seen that when it is desired to clean this valve, it will simply be necessary to remove the heads 19 and 20 thus permitting the core to be drawn out of the casing or cylinder 18. It should be further noted that the rotation of this valve core will cause the carbon to be prevented from accumulating as the carbon will be cut from about the upper ends of the ports 13 and will be carried out with the exhaust. Therefore a tight valve will always be provided and leakage will be prevented from accumulated carbon.
- 30 It will be further noted that by having the exhaust gases passing about the tube 26, the live gases will be heated just prior to en-

tering the cylinders, thus causing a good combustion and further permitting a low grade of fuel such as kerosene to be used.

35

What is claimed is:—

The combination with a pair of engine cylinders having ports in their upper ends, and a cylindrical valve casing overlying said cylinders; of a rotory valve mounted in said casing and having a stub shaft extending through one end thereof, the valve comprising a tubular core opening out the other end of the valve and communicating with a source of combustible mixture supply, and sleeves 40 fast around said core and having ports respectively opening through them into the interior of the core at diametrically opposite points and adapted to communicate with the cylinders alternately, the shells of the sleeves 45 also having diametrically opposite outlet ports communicating with the chambers around said core, and the valve having an annular channel at its midlength communicating constantly with both said chambers 50 and with an exhaust port, and means applied to said stub shaft for rotating the valve.

In testimony whereof I affix my signature in presence of two witnesses.

ALFRED MOLSTAD.
